US0D1019600S

(12) **United States Design Patent** (10) **Patent No.:** **US D1,019,600 S**
(45) **Date of Patent:** **** Mar. 26, 2024**

(54) **HEADPHONE**

- (71) Applicant: **Sonos, Inc.**, Santa Barbara, CA (US)
- (72) Inventors: **Vincent Shyu**, Santa Barbara, CA (US); **Aki Laine**, Santa Barbara, CA (US); **Dana Krieger**, Santa Barbara, CA (US); **Philippe Vossel**, Wuppertal (DE)
- (73) Assignee: **Sonos, Inc.**, Santa Barbara, CA (US)
- (***) Term: **15 Years**
- (21) Appl. No.: **29/869,395**
- (22) Filed: **Dec. 29, 2022**

Related U.S. Application Data

- (63) Continuation of application No. 29/864,135, filed on May 10, 2022, now Pat. No. Des. 974,327, which is a continuation of application No. 29/737,182, filed on Jun. 5, 2020, now Pat. No. Des. 954,019.

(57) **CLAIM**

The ornamental design for a headphone, as shown and described.

DESCRIPTION

FIG. 1 is a perspective view of a headphone showing the new design;

FIG. 2 is a second perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The features shown in broken lines do not form part of the claimed design.

1 Claim, 7 Drawing Sheets
